(57) **CLAIM**

The ornamental design for luminaire, as shown and described.

DESCRIPTION

FIG. 1 is a front view of the luminaire showing a first embodiment of my new design;

FIG. 2 is a back view thereof;

FIG. 3 is a left side view thereof. The right side view is a mirror image of the left side view and therefore, has been omitted;

FIG. 4 is a top view thereof. The bottom view is a mirror image of the top view and therefore, has been omitted; and, FIG. 5 is a front view of a second embodiment of the design for a luminaire having a junction box cover, wherein the length of the luminaire is indeterminate. With the exception of length, it is understood that all of the views are identical to the views of the third embodiment.

The broken line showing of environmental structure is for illustrative purposes only and forms no part of the claimed design.
